UNITED STATES PATENT OFFICE.

FRANK H. ELLIS, OF SOMERVILLE, MASSACHUSETTS, ASSIGNOR TO BARBOUR-
STOCKWELL COMPANY, A CORPORATION OF MASSACHUSETTS.

SPRING LOCKING MECHANISM FOR RAILWAY-SWITCHES.

1,088,266.

Specification of Letters Patent. Patented Feb. 24, 1914.

Application filed May 9, 1910. Serial No. 560,173.

To all whom it may concern:

Be it known that I, FRANK H. ELLIS, a citizen of the United States, residing in Somerville, county of Middlesex, Commonwealth of Massachusetts, have invented certain new and useful Improvements in Spring Locking Mechanism for Railway-Switches, of which the following is a specification, reference being had to the drawings accompanying the same and forming a part thereof.

My invention relates to a spring-locking mechanism for railway switches.

The objects of my invention are to provide an adjustable spring-locking device for switches that is simple in construction, and that can be quickly adjusted to the desired position by the use of a lever or switch-stick, without any change in the relative positions of the coöperating parts.

In the drawings which accompany this specification and form a part thereof my Figure 1 is a plan of a switch with my spring-locking device attached showing the locking-spring in a central position and the switch-tongue thrown to the right and locked; Fig. 2 is a similar view with the switch-tongue thrown to the left and locked; Fig. 3 is a vertical section through line 3—3, Fig. 1; Fig. 4 is a plan of a section of a switch with the spring-locking device moved to the left of the extreme of its adjustment in that direction; and Fig. 5 is a plan of a section of the switch with the spring-locking device moved to the right to the extreme of its adjustment in that direction.

The body of the switch 1 has united to it, preferably by casting, sections of rails 3, 40 and 4, 4. The rails may be attached in any other way if desired. To the top of the body 1 I preferably secure a plate 5 by means of the bolts 6, 6, etc. The plate 5 is provided with track surfaces 7 to match the tread of the abutting rails, and a guard 8. The switch-tongue 9 is pivoted at the heel 10 to the plate 5 and the body 1 in the usual manner and so as to swing on its pivot.

The spring-locking device for locking the switch-tongue 9 in position consists of the box 11 secured to or formed upon the body 1, as desired. The box 11 is provided with the three rounded notches 12, 13 and 14 positioned in a circle circumscribed about the pivot 21 and arranged to receive a rounded

projection 15 formed upon the end of the spring-case 16. The spring-case 16 is a hollow shell formed to receive the spring 17. One end of the spring 17 abuts against the end of the case 16; its other end abuts against the washer 18 which is mounted in the eyebolt 19. The position of the washer 18 may be changed or adjusted to increase or decrease the tension of the spring 17 by means of adjusting nuts 20.

The eyebolt 19 has a pin 21 inserted transversely so that the ends of the pin 21 project beyond the opposite sides of the eyebolt. The pin 21 is movably seated in the circular recesses 22, 22, formed in the bell crank lever 23. The bell crank lever is in turn provided with the projecting pins 24, 24, extending transversely of it, which are movably seated in a circular socket 25. The free end 26 of the lever 23 is pivoted by the pivot 27 to the switch-tongue operating-bar 28. The bar 28 extends transversely of the body of the switch 1 in a guiding slot 29 and has projections 30, 30, extending above its upper face between 80 which is seated the switch-tongue 9 so that longitudinal movement of the operating-bar 28 will cause a lateral movement of the switch-tongue 9. Likewise, a lateral movement of the switch-tongue 9 will cause a longitudinal movement of the bar 28.

When the projection 15 of the spring-case 16 is adjusted to the middle notch 13 the switch-tongue can be locked to either the right or left extreme of its throw, for the arms of the bell crank lever 23 are so proportioned that when the tongue is thrown to the right, as shown in Fig. 1, a line drawn between the center of the notch 13 and the center of the pivot 24 will pass to the left of the pivot 21 in the eyebolt 19, so that tension of the spring 17 exerted through the eyebolt 19 upon the bell crank lever 23 will tend to hold the switch-tongue 9 in its right hand position. Likewise, in Fig. 3, the tongue 9 is moved to the extreme left, thus moving the bell crank lever 23 until a line drawn from the center of the notch 13 to the center of the pivot 24 will pass to the right of the pivot 21, thus demonstrating that the line of tension exerted by the spring 17 through the eyebolt 19 upon the bell crank lever 23 tends to lock the switch in its extreme left position against displacement.

If it be desired to make of the switch what is termed a "spring-switch"; *i. e.*, to so adjust the spring-locking device that the switch-tongue will be spring-locked in its right hand position, as shown in Fig. 1, the spring-case 16 would be moved to the left until the projection 15 would rest in the notch 12, as shown in Fig. 4. In this position forcible movement of the switch-tongue 10 to the left, through the flange of a car-wheel forcibly passing through the switch, would compress the spring 17 through the eyebolt 19 by said movement of the switch, but would not permit enough rotative movement 15 of the bell crank lever 23 to allow the pivot 21 to pass by a line drawn from the center of the notch 12 to the center of the pivot 24, so that the tension of the spring 17 would at all times be exerting force tending to retain 20 the switch-tongue 9 in its right hand position; hence when a car-wheel passed beyond the switch-tongue it would immediately snap over to its extreme right hand position and the spring-locking device would automatically 25 assume the position shown in Fig. 4. Likewise, if the spring-case 16 was moved until the rounded projection 15 rested in the notch 14, the spring would exert its tension in a line tending to hold the switch-tongue 30 always in an extreme left hand position, and the spring-locking device would assume the position shown in Fig. 5; thus if a car passes from the siding to the main track, the tongue would be forced over to the right 35 against the tension of the spring 17, but immediately the flange of the wheel passed beyond the end of the tongue, the spring 17 and intervening mechanism would tend to immediately throw the switch-tongue to the 40 left, as shown in Fig. 2.

From the description it will be seen that the locking device may be set so as to retain the tongue either in a left or a right hand position, as desired; or it can be set to a 45 position to retain the tongue in a right hand position only; or as shown in Fig. 5, to a left hand position only; thus making three points of adjustment without detaching any of the operating parts or changing their 50 positions with relation to each other.

In practice, the box 11 is provided with a detachable cover to cover up the mechanism which may be readily taken off by a railway employee, such as a motorman or conductor, 55 a switch-stick used to pry the spring-case 16 over to any of the positions desired, and the cover replaced. To enable the ready adjustment of the spring-case by means of a

lever or switch-stick, I provide notches 31, 31, into which the end of the switch-stick or lever may be inserted in order to get a leverage upon the spring-case 16.

Various changes may be made in the form of the mechanisms shown, as well as in the location of the parts, without departing 65 from the spirit of my invention.

What I claim is:—

1. In a switch, a laterally movable tongue; a spring-actuated locking mechanism for yieldingly locking said tongue, comprising 70 a slide-bar engaging with the tongue; a rocking lever pivoted to the slide-bar; and an adjustable spring-actuated member pivoted to said lever, arranged to permit its free end to be moved into either of a plurality 75 of bearings to change the direction of the thrust of the spring with reference to the lever, to hold the tongue in either of its operative positions.

2. In a switch, a laterally movable switch-tongue; a spring-actuated slide-bar engaging 80 said switch-tongue; a lever pivoted to said slide-bar; a fulcrum formed in said lever; a bearing for said fulcrum; a spring-actuated member pivoted to the free end of 85 said lever; and a plurality of bearings for the free end of said spring-actuated member to change its direction of thrust to yieldingly hold the switch-tongue in one or the other of its operative positions, as desired. 90

3. In a switch, a spring-actuated locking mechanism for yieldingly locking the switch-tongue, comprising a slide-bar engaging the switch-tongue; an oscillating lever pivoted to the slide-bar; a fulcrum 95 formed on said lever; a bearing for said fulcrum; a bearing on the other end of said lever; a spring-actuated member having a pivot at one end to fit into said bearing; an adjustable collar on said spring-actuated 100 member arranged to form a bearing for one end of a spring; a spring-case forming a bearing for the other end of said spring; and a plurality of bearings located in a circle about the pivot of the lever arranged 105 to receive the free end of the spring-case so as to change the direction of thrust of the spring.

In testimony whereof, I have hereunto set my hand, in the presence of two subscribing witnesses, this the sixth day of May, A. D. 1910.

FRANK H. ELLIS.
